US0D1042943S

(12) **United States Design Patent** (10) **Patent No.:** **US D1,042,943 S**
(45) **Date of Patent:** **** Sep. 17, 2024**

(54) **LIGHTING BAFFLE COMPONENT**

(71) Applicant: **ABL IP Holding LLC**, Atlanta, GA

(US)

(72) Inventors: **Andrew E. Rabin**, Morton Grove, IL
(US); **Darcie Callison**, Palatine, IL
(US)

(73) Assignee: **ABL IP Holding LLC**, Atlanta, GA
(US)

(**) Term: **15 Years**

(21) Appl. No.: **29/766,892**

(22) Filed: **Jan. 19, 2021**

(51) **LOC (14) Cl.** **26-05**

(52) **U.S. Cl.**

USPC **D26/120; D26/85**

(57) **CLAIM**

The ornamental design for a lighting baffle component, as shown and described.

DESCRIPTION

FIG. 1 is a rear elevation of the lighting baffle component; FIG. 2 is a front elevation of the lighting baffle component; FIG. 3 is a top plan view of the lighting baffle component; FIG. 4 is a bottom plan view of the lighting baffle component; FIG. 5 is a right side elevation of the lighting baffle component; FIG. 6 is a left side elevation of the lighting baffle component; FIG. 7 is a perspective view, as seen from above, of the lighting baffle component; FIG. 8 is a perspective view, as seen from below, of the lighting baffle component; FIG. 9 is a perspective view, as seen from above, of the lighting baffle component, in an environment of use; FIG. 10 is a perspective view, as seen from below, of the lighting baffle component, in an environment of use; and, FIG. 11 illustrates the lighting baffle component, exploded from the environment of use shown in FIG. 10. The evenly spaced broken lines in the drawings illustrate environmental structure and form no part of the claimed design.

1 Claim, 9 Drawing Sheets
